UNITED STATES PATENT OFFICE

HENRY B. KIEFER, OF LOUISVILLE, KENTUCKY

ADJUSTING MEANS FOR GARMENTS

Application filed September 4, 1928. Serial No. 303,868.

This invention relates to adjusting means for garments, such for example as caps, and more particularly to an adjusting means comprising interlocking members one of which is formed of a plurality of pivoted sections 5 foldable upon each other to vary the over-all length of the member and each of which has a slot registerable with those in the adjacent sections when the latter are folded upon each other; the other member comprising an arm 10 having at its end a tongue so formed that in locked position of the members it extends transversely of the slot or superposed slots of one or more sections of the first-named member and is engaged thereby to prevent accidental displacement, the sections of the first member being marked according to different head sizes whereby proper adjustment of a cap can be quickly and accurately effected 15 without previous fitting to the head of a wearer; all as hereinafter more specifically described and as claimed.

One of the objects of my invention is to provide means for adjusting the head sizes of 20 caps wherein two interlocking members are provided, one of which may be increased or decreased in length as desired so that overlap of the interlocking parts and consequent unsightly appearance will be prevented.

Another object of my invention is to provide an adjustment for caps comprising interlocking members, one of which is articulated and comprises sections foldable upon each other, the other member being engageable with one of said sections or a plurality of 25 them when folded together.

A further object of my invention is to provide an adjustable means for varying the head sizes of caps, comprising interlocking members one of which is composed of a plurality of foldable sections each marked according to a head size, the markings being so affixed that as each section is folded the marking on the end section will indicate the size 30 to which adjustment is made, the markings of the folded sections being hidden.

Other and further objects will be apparent from the following description and drawing in which—

50 Figure 1 is a front elevation view of a cap

provided with the adjustable means comprising the present invention.

Figure 2 is an enlarged view in elevation of the adjustable means shown in Figure 1, the members being interlocked.

Figure 3 is a top plan view of the adjustable means showing the outermost section folded upon that adjacent to it and the respective members interlocked.

Figure 4 is a front elevational view of one 55 of the interlocking members showing a modified form of construction.

Figure 5 is a rear elevational view of the form of invention shown in Figure 4.

Figure 6 is a perspective view of the other 60 of the interlocking members.

Referring more particularly to the drawing:

A cap 10 is provided with straps 11 and 12 to the free ends of which members 13 and 14 are attached by eyelets 15, or in any other suitable manner such as, for example, by clinched prongs, rivets or stitching.

The member 13 is composed of a plurality of sections 16 which are preferably connected 75 by eyelets 17 so that they may be swung or folded one behind the other thereby to vary the over-all length of the member. Each of the sections 16 is formed with a slot 18, preferably of rectangular shape and extending 80 transversely of the section, the respective slots being so positioned that when one or more of the sections are in overlapped position, having been folded, the slots will accurately register for a purpose which will be 85 hereinafter described.

Except for the innermost section which is fastened to strap 11 the sections 16 are all of similar size and shape, and are similarly formed with slots 18 and holes at their ends 90 for the reception of eyelets 17 or rivets if desired. They may therefore be made in quantity and may be cheaply and quickly assembled.

An alternative form of invention is shown 95 in Figures 4 and 5 of the drawing, wherein each section 16' is formed at one end with punched up ears 19 bent to engage in the circular opening 20 of the adjacent section and thereby retain the whole assembled. Slots 100

18' are formed as in the previously described form of my invention.

Member 14 is provided for interlocking with the member 13 and it comprises an arm 20 terminating in a tongue 21 bent inwardly and twisted so that when the members are interlocked the tongue will be positioned at right angles to the length of slots 18 in member 13. It is obvious that the positioning of the slots and cooperating tongue can be reversed without affecting my invention, the specific form shown being merely for the purpose of illustration.

As is shown in Figure 2 each of the sections 15 16 is marked to correspond to a head size and the sections are so assembled that when the outermost is folded it will lie behind the next adjacent section and its marking, consequently, will be hidden from view. Thus, the outermost visible marking will indicate the head size to which adjustment is made.

The respective sections being foldable upon each other provide a means for varying the over-all length of member 13 so that 25 it will not overlap member 14 when the two are interlocked. A bulky, unsightly appearance is thus prevented. When the sections are so folded the slots therein will register and the bent end of arm 20 being of greater length 30 than the combined thickness of the folded sections the tongue 21 may be passed through the superposed slots and engaged to hold all of the previously folded sections in position.

From the foregoing it will be apparent that 35 I have provided a cheap, easily assembled and convenient means for adjusting caps to various head sizes, such adjustment being variable as desired but not capable of accidental displacement, and such means further providing an extensible member which in folded position occupies little space and without overlapping its complementary interlocking member.

Having described my invention what I 45 claim is:

1. Adjusting means for varying the head sizes of caps comprising an articulated member composed of a plurality of hingedly connected similar sections each of which is 50 formed with a slot, the slots being registrable when the sections are folded to vary the over-all length of said member, a second member separably connected with the articulated member formed from the similar sections, a 55 tongue formed on said second member engageable with said slots when the first-named member has been adjusted to the desired length and adapted to interlock with said slots.

60 2. Adjusting means for varying the head sizes of caps comprising an articulated member fastened to one side of a cap, the sections of said member being similarly formed and foldable one upon another, each section bearing 65 a number corresponding to a head size,

the sections being so assembled that when one is folded behind another the number which it bears will be hidden, each section having a slot adapted to register with the slot of its adjacent section when the sections are folded, and a second member separably connected with the articulated member formed from the similar sections, said second member being fastened to the other side of the cap and engageable at its free end with the slot presented by the outermost section of the adjusted first-named member and the slots of any other section which may be folded behind it.

70 3. Adjusting means for varying the head size of caps comprising a member having a part for attachment to a cap and a plurality of similarly formed sections formed with holes at their ends and intermediate transverse slots, the adjacent ends of said sections being in overlapping relation and pivotally connected so that they may be folded one upon the other to vary the over-all length of said member, a second member attached to the cap and having an inwardly bent arm terminating in a tongue at an angle to the length of the slots in the sections of said first named member and adapted to interlock with the slot presented by the outermost section and the slots of any other sections which may be folded behind it.

75 4. Adjusting means for varying the head size of caps comprising a member having a part for attachment to a cap and a plurality of similarly formed sections formed with holes at their ends and intermediate transverse slots, the adjacent ends of said sections being in overlapping relation and pivotally connected so that they may be folded one upon the other to vary the over-all length of 80 said member, a second member attached to the cap and having an inwardly bent arm terminating in a tongue at an angle to the length of the slots in the sections of said first named member and adapted to interlock with the slot presented by the outermost section and the slots of any other sections which may be folded behind it.

85 5. Adjusting means for garments comprising a plurality of similarly formed sections pivotally connected to each other and attached at one end to a garment, the sections each being formed with a slot which, when the sections are folded one upon another, registers with the slot in each adjacent section, and a member provided with slot engaging means adapted to interlock with the registering slots of the sections when folded to the desired length.

90 In testimony whereof I affix my signature.
HENRY B. KIEFER.
